UNITED STATES PATENT OFFICE

CARL E. RIDGWAY, OF SEATTLE, WASHINGTON

CONTAINER LABEL

Application filed July 30, 1927. Serial No. 209,531.

The invention is a label that is particularly adaptable to be placed around cans and is provided with means to prevent a white spot showing at one edge of the lap.

5 The object of the invention is to provide means for obliterating the white spot at the edge of a can label lap.

Another object of the invention is to provide means for obliterating the white space 10 showing at the end of the printed matter of a can label lap which will at the same time permit the corners of the label to be gummed.

15 And a still further object of the invention is to provide a can label in which the color of the label extends all the way to the end of the label at the ends of the paste strip.

With these ends in view the invention embodies a label in which the color of the label extends all of the way to the ends at the edges.

20 Other features and advantages of the invention will be seen from the following description taken in connection with the drawings wherein,

Figure 1 is a view showing a can with a 25 white space that normally shows at the edge of the lap filled in with diagonal lines.

Figure 2 is a view showing a label with the corners at the end of the paste strip covered with diagonal lines.

30 Figure 3 is a view showing a corner of a label in which the color of the label extends across the ends of the paste strip.

Figure 4 is a view showing a corner of a 35 label in which the corners at the ends of the paste strip are covered with dots which may be of the same color as the body of the label.

In the drawings the label is shown as it would be made wherein numeral 1 indicates the body of the label, numeral 2 the paste 40 strip and numeral 3 the corners at the ends of the paste strip.

In the label shown in Figure 2 the corners 3 are covered with fine diagonal lines of the same color as the body of the label. It is understood however that these lines may be placed in any other direction other than being diagonal as shown. It will be observed that the white spaces between the lines will provide ample adhering surface for the paste 45 so that the lap will be held along its entire

length. These lines will at the same time at least partially obliterate the glaring white space that normally exists due to the inability of the wrapper to match the ends exactly.

In the design shown in Figure 3 the color 55 of the label extends all of the way to the end in a solid mass. This is not as preferable as the design shown in Figure 2 as it has been found that the corners of the label will not adhere to the solid mass of ink so that with 60 this arrangement the corners do not stick.

In the design shown in Figure 4 the color 65 is placed on the space with fine dots so that there is white space between the dots to which the paste will adhere.

It will be understood that changes may be made in the construction without departing from the spirit of the invention, one of which changes may be in the exact shape or design of the corner, another may be in the 70 making of the entire borders at both edges of the diagonal lines with white spaces between them as indicated in Figure 3, and still another may be in the use of other means, other than the diagonal lines or dots to partially cover the surface.

Having thus fully described the invention what I claim as new and desire to secure by Letters Patent, is:

1. In a label in which the entire surface, 75 with the exception of a narrow strip at one edge, is tinted and covered with printed matter and illustrations, tinting at the corners of the said narrow strip, said tinting at the corners having white spaces therein.

2. In a colored label having an uncolored 80 paste strip at one edge, and coloring with white spaces therein at the ends of the said paste strip.

3. In a label covered with coloring and 85 printed matter and having a narrow uncolored strip at one edge with coloring at the ends thereof, means in the colored area at the ends thereof for permitting paste to adhere thereto.

In testimony whereof I affix my signature.
CARL E. RIDGWAY.
